MODULATION SYSTEM

William M. Hall, Lexington, Mass., assignor to
 Raytheon Manufacturing Company, Newton,
 Mass., a corporation of Delaware

Application June 22, 1945, Serial No. 600,861

2 Claims. (Cl. 332—5)

1

My present invention relates to magnetron oscillators, and more particularly to modulating systems therefor.

The magnetron oscillators to which my present invention has special reference generally consist of a cylindrical anode member, made of highly conductive material, such as copper, and provided with a plurality of inwardly-directed, radially-disposed vanes, each pair of adjacent vanes, together with that portion of said cylindrical anode member lying therebetween, constituting a cavity resonator at the frequency desired of the output of the device. Coaxial with said cylindrical anode member is an indirectly-heated cathode member comprising a suitable sleeve provided with a highly electron-emissive coating, for example, of the well known alkaline-earth metal oxide type. Means are incorporated in the device for establishing a magnetic field in a direction transversely of the electron path between said cathode and anode members.

When a proper voltage is applied between the cathode and anode members of such a device, and the magnetic field thereof is appropriately adjusted with respect to the electric field created by said voltage, electromagnetic oscillations are generated having a wave length determined, primarily, by the geometry of the elements making up the aforementioned cavity resonators. Power is extracted from the device, for example, by introducing a loop into one of said cavity resonators, said loop coupling with the magnetic components of said electromagnetic oscillations.

Now, it is known to amplitude modulate such a magnetron oscillator by varying to amplitude modulate such a magnetron oscillator by varying the voltage between the cathode and anode members thereof in accordance with the modulating signal; but, inasmuch as the output voltage of such an oscillator is a power function of the input signal thereto, considerable distortion is obtained, and relatively complex mechanisms have to be resorted to in order to compensate for such distortions.

It is, therefore, the main object of my present invention to accomplish such amplitude modulation without the introduction of distortion.

It is a further object of my present invention to attain this highly desirable result in a simple and inexpensive manner.

These, and other objects of my present invention, which will become more apparent as the detailed description thereof progresses, are attained, briefly, in the following manner:

If the product of the ratio of the voltage output

5 to the voltage on the magnetron and the ratio of the voltage on the magnetron to the voltage input is maintained constant, there is no distortion. In other words, the ratio of the voltage on the magnetron to the voltage input thereto must be the reciprocal of the ratio of the voltage output to the voltage on the magnetron; and I have found that, because of the non-linear relationship between the input voltage and current of the magnetron, this constant product can be attained by inserting an appropriate series impedance intermediate the magnetron and the source of modulating voltage. By so doing, a non-linear drop across said impedance is obtained, which distorts the voltage actually applied to the magnetron in a manner inversely to the distortion in the output, cancelling the latter and resulting in a linear relationship between said output and the modulating input signal.

20 In the accompanying specification I shall describe, and in the annexed drawing show, an illustrative embodiment of the modulation system of my present invention. It is, however, to be clearly understood that I do not wish to be limited to the details herein shown and described for purposes of illustration only, inasmuch as changes therein may be made without the exercise of invention and within the true spirit and scope of the claims hereto appended.

25 In said drawing,

Fig. 1 is a schematic diagram of a magnetron modulating system assembled in accordance with the principles of my present invention;

Fig. 2 is a graph showing the relationship between the input and output with and without employing the expedients of my present invention; and

Fig. 3 is a graph explaining the manner in which my present invention operates to correct for the distortions normally present in amplitude modulating magnetron oscillators.

Referring now in more detail to the aforementioned illustrative embodiment of my present invention, and with particular reference to Fig. 1 of the drawing, the numeral 5 schematically indicates a magnetron, which, as set forth in earlier portions of this specification, may comprise a cylindrical anode member 6, provided with a plurality, here shown as eight, of anode vanes 7 arranged to define a plurality of cavity resonators 8. Centrally disposed with respect to the anode member 6 is a suitable electron-emitting cathode member 9, and while, in the interests of clarity, it has been omitted from the drawing, it will be understood that the device includes means for

establishing a magnetic field in a direction perpendicular to the electron path between the cathode member 8 and the anode vanes 7. Power may be extracted from the device by means of a coupling loop 10.

The anode and cathode members are connected, through conductors 11 and 12, to a power supply for impressing a suitable D.-C. voltage therebetween, the anode conductor 11 including the secondary winding 13 of a transformer 14, whose primary winding 15 may be connected to an appropriate source of modulating voltage, whereby the cathode-anode potential may be varied to amplitude modulate the oscillating output of the device. However, with the device as thus far described, the voltage output varies with the voltage input as shown by the graph labelled "V_{out}. vs. V_{in}. without Z₀" in Fig. 2 of the drawing, this relationship resulting, of course, in considerable distortion.

By means of my present invention, I am able to obtain a relationship such as is shown in the same figure by the graph labelled "V_{out}. vs. V_{in}. with Z₀," a more nearly linear relationship which eliminates the aforementioned distortion.

I attain this relationship by inserting a series impedance Z₀, preferably a resistor, intermediate the anode member 6 of the magnetron and the combined D.-C. and A.-C. voltage input thereto. Inasmuch as the magnetron presents a non-linear impedance to its input voltage, the drop across the impedance Z₀ increases non-linearly with increasing input voltage, and the voltage actually applied to the magnetron varies in a manner, as shown by the graph labelled "V_{mag.} vs V_{in}. with Z₀" in Fig. 3 of the drawing, inversely to the output voltage curve in the absence of the impedance Z₀, shown in Fig. 2 of the drawing.

In said Fig. 3, the dotted lines labelled "IZ₀" indicate the increasing drops across the impedance Z₀, the sum of these drops and the voltage actually applied to the magnetron equalling the entire voltage input, labelled "IZ₀+V_{mag.}".

It will thus be seen that the ratio V_{mag.}/V_{in}. can, by choosing the proper value for the impedance Z₀, be made the reciprocal of the ratio V_{out}/V_{mag.}, the condition necessary to obtain a linear relationship between the voltage output of the oscillator and the voltage input thereto.

It might be pointed out that while the impedance Z₀ has here been shown to be an element in itself, said impedance may, if desired, consist,

for example, of the internal plate resistance of a modulator tube, multiplied, if necessary, by an appropriate factor through the use of a suitable output transformer.

5 This completes the description of my present invention. It will be noted from all of the foregoing that I have provided simple and inexpensive means for enabling the modulation of a magnetron oscillator in such manner that the output voltage varies linearly with the input voltage, whereby distortion is eliminated.

10 Other advantages of my present invention will readily occur to those skilled in the art to which the same relates.

15 What is claimed is:

1. In combination: a magnetron oscillator; a source of modulating voltage therefor; and means for rendering the output voltage of said oscillator substantially linearly variable with said modulating voltage; said means comprising an impedance connected in series intermediate said oscillator and said source of modulating voltage; said impedance being of such value that the ratio of the voltage on said oscillator to said 20 modulating voltage is approximately the reciprocal of the ratio of the oscillator output voltage to said modulating voltage in the absence of said impedance.

2. In combination: a magnetron oscillator; a source of modulating voltage therefor; and means for rendering the output voltage of said oscillator substantially linearly variable with said modulating voltage; said means comprising a resistor connected in series intermediate said oscillator 25 and said source of modulating voltage; said resistor being of such value that the ratio of the voltage on said oscillator to said modulating voltage is approximately the reciprocal of the ratio of the oscillator output voltage to said modulating voltage in the absence of said resistor.

40 WILLIAM M. HALL.
